UNITED STATES PATENT OFFICE

148,790

DESIGN FOR A CAMERA PLATE

Miller R. Hutchison, Jr., Rochester, N. Y., assignor to Eastman Kodak Company, Rochester, N. Y., a corporation of New Jersey

Application November 28, 1947, Serial No. 142,851

Term of patent 14 years

(Cl. D61—1)

To all whom it may concern:

Be it known that I, Miller R. Hutchison, Jr., a citizen of the United States, residing at Rochester, in the county of Monroe and State of New York, have invented a new, original, and ornamental Design for a Camera Plate, of which the following is a specification, reference being had to the accompanying drawings, forming a part thereof, in which

Fig. 1 is a front perspective view of a camera plate showing my new design;

Fig. 2 is an end elevation of the camera plate shown in Fig. 1;

Fig. 3 is a top plan view of the camera plate shown in Fig. 1.

I claim:

The ornamental design for a camera plate, as shown.

MILLER R. HUTCHISON, JR.
